DESIGN FOR A COAT

Jules Freedman, New York, N. Y.

Application December 14, 1945, Serial No. 124,723

Term of patent 3½ years

(Cl. D3—4)

To all whom it may concern:

Be it known that I, Jules Freedman, a citizen of the United States of America, residing in New York city, county of Kings, and State of New York, have invented a new, original, and ornamental Design for a Coat, of which the following is a specification, reference being had to the accompanying drawing, forming part thereof, wherein

I claim:

The ornamental design for a coat, substantially as shown.

JULES FREEDMAN.
